CLAIM

The ornamental design for a barbecue cover support, as shown.

DESCRIPTION

FIG. 1 is a perspective view of a barbecue cover support, showing my new design;

FIG. 2 is a side elevational view thereof;

FIG. 3 is a top plan view thereof;

FIG. 4 is a rear elevational view thereof;

FIG. 5 is a perspective view of a barbecue cover support showing a modified form of my new design; and

FIG. 6 is a right side elevational view of the modified form.

FIG. 1

FIG. 2

FIG. 3

FIG. 4

FIG. 5

FIG. 6
